UNITED STATES PATENT OFFICE.

JOHN Z. COBLENS, OF NEW YORK, N. Y.

DESIGN FOR A FABRIC.

SPECIFICATION forming part of Design No. 17,919 dated December 6, 1887.

Application filed September 9, 1887. Serial No. 249,281. Term of patent 3½ years.

To all whom it may concern:

Be it known that I, JOHN Z. COBLENS, of the city, county, and State of New York, have invented a new and Original Design for Fabrics, of which the following is a full, clear, and exact description.

The nature of my design is fully represented in the accompanying drawing, to which reference is made.

10 The design consists of the two facing triangles *a b*, which together form a square, *A'*, at one corner of a large square, *A*. Adjacent to the side of the triangle *a* appears the right-angled block *c*. In the complete pattern I employ four of the squares *A'*, each ornamented with two triangles and a right angle, but with the triangles *a* reversed in relative position, as shown in the accompanying drawing. Between the sides of the squares *A'* ap-

pear the short parallel stripes *d d'*, arranged at 20 right angles to each other, and between the ends of the said stripes appear the dots *e*.

I claim—

1. The design for fabric herein shown and described, the same consisting of a hollow 25 square, *A*, and a second smaller square, *A'*, within the square *A* and at one corner thereof, and the two facing solid triangles *a b* within the smaller square *A'*.
2. The design for fabric herein shown and 30 described, the same consisting of the square *A*, ornamented with the two facing triangles *a b* and right angles *c*, and the stripes *d d'* and dots *e*.

JOHN Z. COBLENS.
